UNITED STATES PATENT OFFICE.

GODFREY H. HARRIS, OF NEW YORK, N. Y., ASSIGNOR TO THE DICKINSON HARD RUBBER COMPANY, OF MASSACHUSETTS.

DESIGN FOR A GAME-COUNTER.

SPECIFICATION forming part of Design No. 30,208, dated February 14, 1899.

Application filed January 9, 1899. Serial No. 701,677. Term of patent 31 years.

To all whom it may concern:

Be it known that I, GODFREY H. HARRIS, a citizen of the United States, residing in the city, county, and State of New York, have invented and produced a new and original Design for Game-Counters, of which the following is a specification, reference being had to the accompanying drawings, forming part thereof.

Figure 1 is a plan view of the game-counter, showing my new design, which may be produced upon both sides of said counter. Fig. 2 is a profile view of said counter.

As shown in the drawings, the leading or

material feature of my design consists in a circle inclosing two horseshoes, one overlapping the other, with two riding staff-whips running through the same and crossing each other.

Having described my invention, what I claim as new, and desire to secure by Letters Patent, is—

The design for a game-counter, as herein shown and described.

GODFREY H. HARRIS.
